United States Patent Office

Des. 227,132

Patented June 5, 1973

227,132

PAN FOR COOKING BACON

Roger L. Kelly, Palatine, Ill., assignor to American Home Products Corporation, New York, N.Y.

Filed Oct. 15, 1971, Ser. No. 189,809

Term of patent 14 years

Int. Cl. D7—02

U.S. Cl. D44—1 J

FIG. 1

FIG. 2

FIG. 3

FIG. 4

FIG. 1 is a top plan view of a pan for cooking bacon showing my new design.

FIG. 2 is a front or rear elevational view thereof.

FIG. 3 is a right or left end view thereof.

FIG. 4 is a vertical section taken along line 4—4 of FIG. 1.

I claim:

The ornamental design for a pan for cooking bacon, as shown.
